UNITED STATES PATENT OFFICE.

FRIEDRICH SCHNEIDER AND FRITZ WALther, OF CHICAGO, ILLINOIS.

DESIGN FOR SALT-BOX.

Specification forming part of Design No. 7,458, dated May 26, 1874; application filed April 4, 1874.
[Term of Patent 3½ years]

To all whom it may concern:

Be it known that we, FRIEDRICH SCHNEIDER and FRITZ WALther, of Chicago, in the county of Cook and State of Illinois, have invented a Design for a Salt-Box, of which the following is a specification:

The nature of our design is fully represented in the accompanying illustration, to which reference is made.

The body, A, of our salt-box is a vertical section of a frustum of a cone, secured to a back-board, B, to hang on the wall. C is the lid, pivoted at the rear corners to two metal centers, a. The top, bottom, and side edges

are bound with metal bands b. The whole box is ornamented with inlaid veneers, in diagonal stripes c, of light and dark colored woods, simulating inlaid wooden staves.

What we claim as our invention is—

A design for a salt-box, of the form shown, ornamented with the inlaid veneers, as shown and set forth.
